CLARENCE S. SNAVELY, OF PITTSBURGH, PENNSYLVANIA, ASSIGNOR TO THE UNION
SWITCH & SIGNAL COMPANY, OF SWISSVALE, PENNSYLVANIA, A CORPORATION OF
PENNSYLVANIA

LIGHT SIGNAL

Application filed October 19, 1923. Serial No. 669,488.

My invention relates to light signals, and is particularly adapted for signals of this type used in railway traffic controlling systems.

5 I will describe one form of light signal embodying my invention, and will then point out the novel features thereof in claim.

In the accompanying drawings, Fig. 1 is a view showing in front elevation one form 10 of light signal embodying my invention. Fig. 2 is a rear view of the signal shown in Fig. 1. Fig. 3 is a vertical sectional view along the line III—III of Fig. 2. Fig. 4 is a horizontal 15 sectional view on the line IV—IV of Fig. 3, looking in the direction of the arrows. Fig. 5 is a detail view showing, in elevation, the back light reflector for the signal illustrated in the first four views. Fig. 6 is a detail view showing the back light housing as viewed 20 from the right in Fig. 2.

Similar reference characters refer to similar parts in each of the several views.

Referring first to Figs. 1, 2 and 3 the signal comprises a triangular front plate 1. The 25 front plate 1 is provided at its top with a yoke 1^a, and at its bottom with two lugs 1^b, by means of which the signal may be adjustably mounted in any desired manner. Three light units R, Y and G are attached to plate 30 1 by means of bolts 4. These light units are so mounted that their centers are at the vertices of a triangle of which one vertex is directed downwardly. Each light unit is contained in a shell designated by the reference 35 character 2 with an exponent corresponding to the unit, and a cover designated by the reference character 3 also with a suitable exponent. These shells 2 are integral with front plate 1.

40 The front plate 1 is provided with three apertures one immediately in front of each light unit. Each aperture is provided with a lens structure forming part of the light unit and which, as here shown comprises a 45 front lens and a back lens designated by the reference characters 11 and 12, respectively, with exponents corresponding to the units. These lens structures are supported in a suitable frame 15 which is supported on plate 1 50 by bolts 4. Behind each lens structure is an

electric lamp, designated by the reference character 13, and also forming part of the light unit, the filament of this lamp being located at the focus of the associated lens combination. Each front lens 11 is protected from snow and from the direct rays of the sun by means of a hood 14 of suitable shape supported by the front plate 1. In addition to the lamp 13, light unit R contains a terminal board C comprising binding posts 14^a 60 which are connected with the lamps 13 of the various units.

Supported by front plate 1 and located in the center of the triangle defined by the three light units is a pin which projects towards the back of the signal and which terminates in a threaded tip 5^a. A Y-shaped spider B is provided with a hole at its center to accommodate the pin 5. Each of the covers 3 is attached, by means of a rivet 6 to the end 70 of one leg of the spider B. It will be noticed that with this method of connection, relative movement of any cover with respect to any other cover is impossible. A nut 8 is threaded on the tip 5^a of pin 5 to force the spider 75 B to the right as viewed in Fig. 3 thus clamping the covers 3 against the edges of their respective shells 2. The nut 8 is provided with a hasp 9 arranged to latch over a staple 10 in the lower leg of spider B. The staple 80 10 is provided with a hole 10^a to receive the yoke of a padlock by means of which the covers may be locked in position since it is obvious that if nut 8 is screwed up and locked, in position the covers cannot be removed. 85

Since the covers are thus rigidly fastened together by means of spider B it is plain that no one cover can be moved away from its associated shell without also removing the other covers from their shells. 90

Since no one cover 3 can be removed without also removing the other two covers, there is no possibility of a false indication due to transmitted light originating behind the signal and passing through one of the colored 95 lenses 11. That is to say, in the event of such a light behind the signal and one of the units being open, the remaining units would also be open and all three lens structures would be 100 equally illuminated.

In order to accommodate the terminal board C the shell 2^R is larger than shells 2^G and 2^Y, and cover 3^R is therefore larger than cover 3^G and 3^Y. It follows that the larger mass of cover 3^Y biases this cover to the position shown in the drawing and hence all covers normally occupy positions immediately behind their respective units.

Means are provided for imparting a distinctive color to the beam of light projected from each light unit. This may be done by giving a distinctive color to one lens, as 11^G of each lens combination. For example, 11^G may be made of green glass, 11^Y of yellow glass, and 11^R of red glass. These colors are in accordance with standard practice in railway signaling and correspond to indications of proceed, caution and stop, respectively.

As is well understood in railway signaling practice, the control of the signal is usually such that as a train passes the signal the lamp 13^R is lighted and the signal projects a beam of red light to indicate to a following train that the block protected by the signal is occupied. It is frequently desirable that an observer located on the train should be able to determine that the stop indication is being displayed after the train has passed the signal. For this reason I provided a back light for unit R which I will now describe. Attached to the frame 15 of lenses 11^R and 12^R is a sheet metal member 16 carrying a collimating lens 17 so disposed as to project a beam of light from lamp 13^R toward the right as viewed in Fig. 2. A housing 18 is attached by means of bolts 18^a to the side of shell 2^R of unit R. This housing is provided with a transparent glass screen or window 19 which is protected by a hood 20. Immediately inside of window 19 and supported also by housing 18 is a reflector device D. As best shown in Fig. 5, this device comprises two side rails 21 and 21^a and a plurality of transverse reflectors 22 fastened at their ends to these rails. These reflectors are here shown as strips of metal having their upper surfaces (Fig. 5) highly polished. The signal is so assembled that the reflector device D is interposed in the beam of light projected from lamp 13^R by collimating lens 17, and the reflectors 22 are so disposed that this beam is redirected toward the rear of the signal through window 19. The path of this beam is indicated by the dot-dash lines on Fig. 4. One surface of window 19 may be frosted or lightly sand-blasted for diffusing the light from reflector device D. It will be noticed that due to the angular position of window 19 the condition of energization of unit R may thus be observed in the rear of the signal, from the right hand side of the signal as viewed in Fig. 2, or from any point between these two positions.

Although I have herein shown and described only one form of light signal em-

bodying my invention, it is understood that various changes and modifications may be made therein within the scope of the appended claim without departing from the spirit and scope of my invention.

Having thus described my invention, what I claim is:

A light signal comprising a front plate, three light units supported by said front plate and each made up of an electric lamp and a lens arranged to project a horizontal beam of light from the lens, said units being arranged in a triangle with two of the units located side by side and the third unit located below and equally distant from the other two units, said lamps being adapted for individual illumination and the lenses of the three units being distinctively colored, enclosing means for said units including a cover for the back of each unit, a Y-shaped spider having one said cover attached to each leg thereof and means for pivotally attaching said spider to said front plate, the cover for the lower unit being heavier than the other covers so that said spider is biased by gravity to a position where in each cover registers with its associated unit.

In testimony whereof I affix my signature.
CLARENCE S. SNAVELY.
